(57) **CLAIM**

I claim the ornamental design for a support arm attachment for a table leg, as shown.

DESCRIPTION

FIG. 1 is an upper front perspective view of a support arm attachment for a table leg of my design;

FIG. 2 is a lower front perspective view thereof;

FIG. 3 is a top view thereof;

FIG. 4 is a bottom view thereof;

FIG. 5 is a quarter right side view thereof;

FIG. 6 is a quarter left side view thereof;

FIG. 7 is a full right side view thereof; and,

FIG. 8 is a full left side view thereof.
